UNITED STATES PATENT OFFICE.

ALBERT WILDEN, OF COLOGNE, GERMANY.

IDENTITY-CARD HOLDER.

Application filed May 18, 1925, Serial No. 31,206, and in Germany November 6, 1924.

Railways, street cars and other concerns which day by day provide for large numbers of people often issue monthly, weekly or suchlike periodic tickets which are not trans-
 5 ferable and must therefore be so connected with the photograph of the holder that an exchange of the appropriate ticket can be made as easily and quickly as possible, but on the other hand must be such that there
 10 is no possibility of deception. Further such tickets or authorizations must possess the properties that they are light and handy, that as little work as possible is entailed on the part of the issuing authorities and a
 15 clear control is assured. The systems hitherto known in no wise fulfill the above stipulated conditions. Either they comprise mechanisms which unintentionally and of their own accord are liable to become de-
 20 ranged or intentionally are readily put out of action, so that an attempt to tamper with these tickets cannot always be detected with certainty, or they even offer the direct possibility for deception by the exchange of
 25 photograph or ticket which cannot be detected so easily, if at all.

The present invention concerns an improved photo frame for tickets or passes of this kind which cannot be surpassed for
 30 simplicity and nevertheless precludes all attempts at deception. For this purpose the improved frame consists of a sheet of metal or the like provided with apertures or windows and bent to U-form, which is closed
 35 on three sides so as to provide a pocket-like slit in which the ticket and photograph are inserted side by side. The photograph is ir-removably fixed in the frame by means of two tongues pressed out of the material of
 40 the frame itself which are adapted to be broken by any attempt to bend them back. Further every frame is furnished with a number impressed therein and if desired with other characters which are also marked
 45 on the ticket when issued so that the ticket can only be used with the proper frame.

In order that the invention may be clearly understood and readily carried into practice same will now be described with reference
 50 to the accompanying drawings showing one embodiment thereof by way of example, and wherein:

Figure 1 is a plan of the improved photo frame according to the invention; Fig. 2 is
 55 a section on line A—A of Fig. 1; Fig. 3 is a section on line B—B of Fig. 1; Fig. 4 is a

section on line C—C of Fig. 1; and Fig. 5 shows the sheet metal frame in plan before bending.

As shown in Fig. 5, the frame consists of 60 a rectangular piece of sheet material the left half of which comprises a pair of large apertures *a*, whilst the right half has two pairs of smaller apertures *b* and *c* respectively. This sheet is doubled over along the center 65 line *e* to U-form, so that the pairs of apertures *a*, *b*, *c* coincide. Then the two laterally projecting flaps *f*, *g*, of the under frame portion are bent round so that the frame is now closed on three sides and only possesses 70 a small slit at the bottom. In this small slit is introduced from below on the left half the appropriate ticket *d* and on the right half the photograph *i*. In order to separate the photograph and ticket the underneath portion of the sheet has an impressed groove *h* which divides the interior of the frame slot into two compartments. Advantageously, in addition, three small rivets are passed through both portions of the sheet, whereby 75 it may be rendered impossible to open out the frame. These rivets may be constituted by the material of the frame itself.

The photograph *i*, preferably provided with a celluloid cover, is now irremovably 80 secured in the frame. One of the strips *k* running across the photograph, comprises two cut-out tongues *l*, whilst the other corresponding strip *m* has a suitable rectangular aperture *n*. By means of a simple closing 85 pressure applied by hand the two metal tongues *l* are pressed inwardly through the photograph with its protecting cover and through the aperture *n*, being finally bent round behind the strip *m*. In this way a 90 photograph is completely held fast with the frame, for which purpose, however, no separate means has been used for the rivet but only the material of the frame itself. The hardness of the sheet material is so selected 95 that if an attempt is made to bend back the tongues these are inevitably broken. As no separate means is used for the rivetting it is therefore impossible to effect a substitution. Moreover if a metal tongue is missing from 100 a frame it is evident that this has been removed by violence for an unauthorized purpose.

As evident from Fig. 1 the frame carries 110 on its left upper cross piece a serial number produced by impressing so that each number can only exist a single time. In issu-

ing the monthly ticket or the like the authorized official writes the frame number in question upon the ticket, whereby the inseparability of this ticket and the particular frame is irrevocably secured. The monthly ticket with its celluloid cover, made out for the journey, is then inserted into the frame. Upon inspection by comparison of the two numbers it can at once be established whether a wrong ticket is in the frame. The issuing authorities have not to expend further labour in the matter. The attachment of the photograph can only be made once, whilst at each renewal of the season ticket to the holder the insertion of his ticket may be done by himself. The ticket and photograph can be seen from both sides so that printing may be appended on the rear side of the ticket and the rear side of the photograph may be provided with a stamp whereby the inspection is endorsed.

In order to prevent accidental displacement of the ticket from the frame the lower cross piece of the frame is provided with an impressed groove *o*, which however is not absolutely necessary. If desired furthermore a perforation *p* may be provided in the lower cross piece if the frame is to be fastened to a chain.

It is evident that the frame having coincident apertures on both sides as above described has also the advantage that if comparatively thin cards are employed for insertion therein, attempts at deception by erasure or alteration of the script or number can very readily be detected by holding the frame against the light. In the same manner it can easily be seen if the traveller has inserted another photograph over that already in place.

The German Government Railway Company (Reichbahngesellschaft) has acknowl-

edged the herein described frame to be the best and most suitable of numerous models, and a large number of the railway directors have already introduced it. On account of its generally handy form and especially on account of the exclusion of all possibility of deception the new photo frame is also suitable for all possible cases where the non-transferring of season tickets or authorized documents are concerned.

I claim:

An identity card holder, comprising a one piece frame of sheet metal of a brittle character bent to a U-form, a flap at each end of one half of the frame, said flaps being adapted to fold over the other half of the frame, the halves of said frame having coinciding inspection apertures in them, two photo inspection apertures being arranged one above the other and side by side with a ticket inspection aperture in each half of the frame, an impressed groove in one of the strips of metal dividing the said apertures from one another, means for permanently securing in said frame a photograph to be displayed through the said photo inspection apertures consisting of tongues formed integrally on one half of said frame and adapted to be passed through said photograph and the other half of the frame and bent over, the material of such tongues being of low pliability such as to insure fracture upon being bent a second time, identification matter, agreeing with corresponding matter on the period ticket, impressed in the metal of the frame, and means for detachably securing in the frame the ticket to be displayed comprising an impressed groove in that part of the frame adjacent to the aperture for the ticket.

ALBERT WILDEN.
